INVENTOR

BY

ATTORNEY

UNITED STATES PATENT OFFICE.

WALTER K. POULSON, OF UPTON, WYOMING.

THREAD-CUTTING DEVICE.

Application filed April 8, 1922. Serial No. 550,714.

To all whom it may concern:

Be it known that I, WALTER K. POULSON, a citizen of the United States, residing at Upton, in the county of Weston and State 5 of Wyoming, have invented new and useful Improvements in Thread-Cutting Devices, of which the following is a specification.

This invention relates to a thread cutting device for thimbles, and the object is to 10 provide, in one form of the article, a cutting blade and a guard member acting as a protecting device.

A further object is to provide in another 15 form of the invention, a cutting edge on the lower rolled portion of the thimble, the edge being protected by deflected portion of the metal partly separated from the base of the thimble in forming the blade.

With the foregoing and other objects in 20 view, the invention consists in the novel construction and arrangement of elements described and claimed, it being understood that modifications may be made within the scope of the claim without departing from 25 the spirit of the invention.

In the drawings:

Figure 1 is a perspective view of a thimble with the improvement applied thereto.

Figure 2 is a fragmentary view, in vertical section, and on an enlarged scale.

Figure 3 is a fragmentary view in vertical section, a portion of the rolled edge and guard being shown in dotted lines.

Figure 4 is a fragmentary view showing 35 another form.

Figure 5 is a fragmentary view, in vertical section, of the form shown in Figure 4.

In carrying out the invention, I employ

a thimble 10 having a lower rolled portion 11. The shield or guard member 12 is 40 formed on the rolled portion, or is soldered thereto, and is spaced from the outer portion or surface of the thimble, the adjacent portion of the surface being designated for convenience 13.

This portion 13 is provided with an opening 14, and the metal being cutaway, or partly cutout, in the formation of the opening, is deflected to form the blade or knife 15, the blade extending directly outward and 50 being positioned behind the guard member. The cutting edge is designated 16.

In another form of the device, the rolled edge 22 is cutaway in the form shown in Figure 4, producing an opening approximately triangular in shape and having an entrance portion 23. The portions 24 and 55 25 project toward each other and are upwardly deflected and the cutting edges 26 may be bevelled as illustrated.

These edges diverge with reference to each other and converge with reference to the lower portion of the slot. The thread engages the cutting edge from either side, according to the convenience of the user of the 65 article.

Having thus described the invention, what is claimed is:

The combination with a thimble having a rolled edge including an upward extension, 70 of a cutting element bent outwardly from the wall of the thimble toward said extension and protected thereby, the extension constituting a guard.

In testimony whereof I affix my signature.

WALTER K. POULSON.
